UNITED STATES PATENT OFFICE.

ALIDOR LEFFÈRE, OF JACKSON, MICHIGAN, ASSIGNOR TO RIVERSIDE FORGE AND MACHINE COMPANY, OF JACKSON, MICHIGAN.

TRIMMING DIE.

Application filed April 28, 1923. Serial No. 635,382.

To all whom it may concern:

Be it known that I, ALIDOR LEFFÈRE, a citizen of the United States, residing at the city and county of Jackson, State of Michigan, have invented certain new and useful Improvements in Trimming Dies, of which the following is a specification.

This invention relates to improvements in trimming dies.

10 The main objects of this invention are:

First, to provide a trimming die for wheel hub forgings which accurately centers and trims the work.

15 Second, to provide an improved trimming die which is of large capacity and at the same time permits uniformly accurate work.

Third, to provide an improved trimming die for hub forgings which is not likely to get out of repair.

20 Objects pertaining to details and economies of construction and operation will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated 30 in the accompanying drawing forming a part of this application, in which:

Fig. I is a detail view, mainly in vertical section on a line corresponding to line 1-1 of Fig. II of my improved trimming die, 35 the male die member or plunger being shown in partially retracted position, a piece of work being illustrated in position and only such parts of the machine being illustrated as are deemed necessary to show an adaptation or embodiment of my invention.

40 Fig. II is a horizontal section on a line corresponding to line 2-2 of Fig. I.

Fig. III is a perspective view of one of the hub forgings prior to trimming.

45 Fig. IV is a perspective view of one of the hub forgings after trimming.

In the drawing similar reference numerals indicate similar parts throughout the views and the sectional views are taken looking in 50 the direction of the little arrows at the ends of the section lines.

Referring to the drawing, 1 represents the bed of the machine of the punch press type, and 2 the plunger. The operating parts of the machine are not illustrated as

they form no part of this invention. Upon the bed 1 I mount a bed member 3 having a shouldered recess 4 in its face, the annular die member 5 being secured in this recess.

The bed member is also provided with a longitudinal bore 6, the die member 5 being concentric relative to this bore. The work centering member 7 is a reciprocating fit within the bore and is yieldingly supported by means of the coiled spring 8 arranged within the bore, the bore having a shoulder 9 at its lower end to support the spring.

This centering member has a seat or socket 10 for the hub portion 11 of the hub forging 12, the seat being conformed so that the hub forging may be dropped into it and is properly centered relative to the dies. As these forgings come from the forging dies they ordinarily have a web or "flash" of metal as 13. It will be understood that no attempt is made to illustrate the relative proportion of "flash" as this is normally irregular.

The work centering member 7 is normally held in the projected position shown to receive the work without danger of its being dropped upon the die, which might chip the same, and also it serves as a stripper or ejector for the work after it has been operated upon.

The male die member 14 is mounted upon the plunger to coact with the female die member and has a longitudinal bore 15 therein in which the work clamp 16 is reciprocatingly mounted, the work clamp having a stem 17 provided with a retaining pin 18 to limit the downward throw of the clamp under its actuating spring 19. The clamp 16 is normally projected and its face is conformed to engage the inner side of the hub forging coacting with the centering member in supporting and centering the same while acted upon by the dies.

Adjustable stop blocks 20 are mounted in slotted brackets 21 on the male die member, set screws 22 being provided for securing these blocks in their adjusted positions. To disengage the "flash" from the male die member I provide segmental strippers 23 which are reciprocatingly mounted on the bolts 24 carried by the lugs 25 on the male die member, springs 26 being arranged between the strippers and these lugs so that the strippers are yieldingly held in their projected position.

With this arrangement of parts I provide a machine which is very accurate, can be operated by workmen not particularly skilled and is of large capacity.

5 I have illustrated and described my improvements as I have embodied them for trimming hub forgings. My improvements may, however, be adapted and are desirable for use in trimming other forgings and parts. I have not attempted to illustrate or 10 describe such embodiments or adaptations as I believe the disclosure made will enable those skilled in the art to which my invention relates to embody or adapt the same as 15 may be desired.

Having thus described my invention what I claim as new and desire to secure by Letters Patent is:

1. In a structure of the class described, 20 the combination of a bed member having a shouldered recess in its face and a central longitudinal bore, an annular female die member seating in said recess, a work centering member reciprocating in said bore and adapted to center the work relative to 25 said female die member, a spring for normally supporting said work supporting member in projected position, a reciprocating male die member having a central longitudinal bore, a work clamping member reciprocating in said bore of said male die member, a spring for yieldingly supporting 30 said work clamping member, strippers mounted on said male die member for reciprocating movement longitudinally thereof, and springs for actuating said strippers. 35

2. In a structure of the class described, the combination of a bed member having a shouldered recess in its face and a central longitudinal bore, an annular female die member seating in said recess, a work centering member reciprocating in said bore and adapted to center the work relative to 40 said female die member, a spring for normally supporting said work supporting member in projected position, a reciprocating male die member having a central longitudinal bore, a work clamping member reciprocating in said bore of said male die member, and a spring for yieldingly supporting 45 said work clamping member.

3. In a structure of the class described, the combination of a bed member having a shouldered recess in its face and a central longitudinal bore, an annular female die member seating in said recess, a work centering member reciprocating in said bore and adapted to center the work relative to 50 said female die member, a spring for normally supporting said work supporting member in projected position, a reciprocating male die member having a central longitudinal bore, a work clamping member reciprocating in said bore of said male die member, and a spring for yieldingly supporting 55 said work clamping member.

the combination of a bed member provided with an annular die member, a work centering member reciprocatingly mounted in said bed member, a spring for yieldably supporting said work centering member, a co-acting male die member, a work clamping member reciprocating in said male die member in alignment with said centering member, a spring for yieldingly supporting said work clamping member, and a stop adjustably mounted on said male die member.

10. In a structure of the class described, the combination of a bed member provided with an annular die member, a work centering member reciprocatingly mounted in said bed member, a spring for yieldably supporting said work centering member, a coacting male die member, and spring actuated stripers reciprocatingly mounted on said male die member.

11. In a structure of the class described, the combination of a bed member provided with an annular die member, a work centering member reciprocatingly mounted in said bed member, a spring for yieldably supporting said work centering member normally above said die member, and a coacting male die member.

12. In a structure of the class described, the combination of a bed member provided with an annular die member, a work centering member reciprocatingly mounted in said bed member, a spring for yieldably supporting said work centering member normally above said die member, a coacting male die member, and stops adjustably mounted on said male die member.

In witness whereof, I have hereunto set my hand.

ALIDOR LEFÈRE. [L. S.]
